UNITED STATES PATENT OFFICE.

FRIEDRICH HERMANN SCHULE, OF HAMBURG, GERMANY.

SEPARATING-MACHINE.

SPECIFICATION forming part of Letters Patent No. 726,996, dated May 5, 1903.

Application filed October 2, 1900. Serial No. 31,786. (No model.)

To all whom it may concern:

Be it known that I, FRIEDRICH HERMANN SCHULE, a subject of the German Emperor, and a resident of Hamburg, in the German Empire, have invented certain new and useful Improvements in Separating-Machines, of which the following is a specification.

This invention has relation to separating or sorting machines; and it has for its object the provision of means whereby the machine is adapted to the separation of various materials.

In the separation or sorting of materials of different specific gravities several factors come into play—first, the difference in the specific gravity of a mixture of different materials or of the same material; second, the form of each of the particles, and, third, the condition of the surface of such particles, whether perfectly smooth or more or less rough or in other condition to result in greater or less friction when moving over a smooth surface. Taking rice as an example, before it is cleaned it contains not only hulls and blind grains lighter than the good ones, but also grains which are partially hulled or not hulled at all, and may contain other seeds. On the other hand, decorticated rice contains not only the perfect grains, but a considerable proportion of imperfect and broken grains, as well as partially-decorticated grains and grains which left the decorticating-machine unaffected. I have in both instances recited not only constituents the specific gravity of which varies considerably, but also constituents the form of which, as well as their frictional resistance to motion over a given surface, varies considerably. It therefore becomes obvious that a perfect separation could not be obtained if the materials in the cases cited were caused to travel over equal smooth-surfaced separating areas. Thus, for instance, in the cleansing of rice the comparatively light hulls and foreign seeds mixed with the grain would travel more slowly than the heavier grains over a smooth horizontally-reciprocating table, for instance, and this difference in the speed of motion would be increased in the case of an inclined table in proportion to its inclination. It becomes obvious at once that if the material were fed

to the table at a fixed point it would not be possible to clean rice and also effectually separate the perfect decorticated rice from imperfect and broken and partly-decorticated or undecorticated grains without difficulty 55 and great loss of time.

My present invention has for its object the provision of means whereby this inconvenience is largely obviated, means being also provided whereby the distance traveled over 60 by the material can be regulated by varying the point at which the material is fed to the table relatively to the points at which the constituents of different specific gravity are discharged; but that my invention may be 65 fully understood I will describe the same in detail, reference being had to the accompanying drawings, in which—

Figure 1 is a side elevation, and Fig. 2 a top plan view, partly in section, of a separating-machine embodying my invention.

The separating-table 2 is secured to longitudinal beams 3, mounted on sectoral rockers 4, the segmental face of which is provided with gear-teeth meshing with racks 5 on a base-plate or on longitudinal beams of a basal framing, and to the longitudinal beams 3 about midway of their length is connected one end of a connecting-rod 6, whose opposite end is connected to a crank 7 on a shaft 8, carrying a belt-pulley 9, driven from any suitable prime motor, the separating-table receiving a to-and-fro motion at right angles to its separating-channels by the mechanism described.

In practice I prefer to connect the connecting-rod to any suitable device for neutralizing shocks or provide such means, which, however, form no part of this invention, which resides, essentially, in the construction of the 90 separating-table or, more properly, the proximate walls of the separating-channels thereof, of which I will now describe, referring to Fig. 2, and before doing so I may state that in practice the said table is more or less inclined in the direction of its separating-channels, according to the materials to be separated, and is provided with a feed-hopper 10, extending the full length of the machine at right angles to its channels and adjustable 100

laterally toward one or the other longitudinal edge for the purpose of varying the distance traveled over by the constituents of a mixture of materials before they are discharged, as hereinabove referred to.

The separating-table 2 is divided into a series of transverse channels 12, the bottom 13 of which is of polished sheet metal. The proximate faces of the vertical walls of the channels have reëntrant angles with a long and a short side connected by a curved or concave portion and may be formed by prismatic blocks of wood 14, suitably spaced and staggered, and to which blocks the sheet-metal walls 15 and the curved plates 16 are secured, so as to form the reëntrant angles 17, whose shorter sides 18 are horizontal and at right angles to the direction of the channels 12, while the longer sides 19 are inclined relatively to said direction of the channels.

As above stated, the series of prisms 14 transversely of the table or parallel with the direction of the channels are staggered, while longitudinally of said table said prisms are arranged in parallel rows and equidistant from each other in both directions.

By the described arrangement the reëntrant angles themselves are staggered in that the apices of the angle of one wall lie opposite and nearly midway the longer sides of the angles of the opposite wall of a channel 12, as clearly shown in Fig. 2.

At each side of the machine extends a receiving-trough 20 and 20', respectively, into which the materials from the separating-channels are discharged and from which troughs the materials are discharged into suitable receptacles.

In consequence of the shaking motion imparted to the table 2 the material fed into the separating-channels is thrown to and fro by the zigzag-shaped channel-walls and is thereby separated in a well-known manner—as, for instance, described in United States Patent No. 559,815—into its heavier and its lighter constituent parts. The former, sliding down the inclined bottoms of the channels in the direction of the arrows *y*, Fig. 2, drop into the trough 20, while the lighter constituents travel

in the opposite direction, arrows *z*, and pass 50 into the trough 20'.

The good operation of the machine depends, essentially, upon the described configuration of the vertical walls of the separating-channels 12 and to a great extent upon the hard 55 polished surfaces with which the materials come in contact and travel along or over. There are, however, other factors to be considered—namely, the degree of inclination of the separating-table, the speed of the reciprocations thereof, the point at which the material is fed to the channels, and the feeding of the materials to the channels. These factors depend, however, exclusively upon the character of the materials to be separated—65 namely, the difference in the specific gravity of the constituents of the material and the frictional resistance to motion of said constituents. There is, however, no difficulty in readily adjusting the inclination of the table, the speed of its reciprocations, the point at which the material is fed to the channels, and the amount of material to be continuously fed to the channels nor are these adjustments required for each mixture of materials of a different character.

Having thus described my invention, what I claim as new therein, and desire to secure by Letters Patent, is—

1. In a machine of the class described, a table 80 divided into channels by partitions, the proximate faces of which are formed by reëntrant angles, a curved plate connecting the sides of each of said angles, and means for shaking said table, substantially as and for 85 the purpose set forth.

2. In a machine of the class described, a table 90 divided into channels the faces of which have reëntrant angles having a short and a long side, and a curved plate connecting substantially the center of the short side with the long side and concentric with the medial line of the angle, for the purpose set forth.

FRIEDRICH HERMANN SCHULE.
